CLAIM

The ornamental design for a football display case, as shown and described.

DESCRIPTION

FIG. 1 is a perspective view of the football display case;

FIG. 2 is a perspective view with the cover removed;

FIG. 3 is a front elevation view, the rear elevation view being identical. The broken line disclosure of the football is for illustrative purposes only and does not form any part of the claimed design;

FIG. 4 is a top view; and,

FIG. 5 is an end view, both ends being identical.

The bottom of the illustrated football display case is planar and unornamented.
